UNITED STATES PATENT OFFICE.

ALFRED MENDEL, OF STREHLEN, NEAR DRESDEN, SAXONY, GERMANY.

COLLAR FOR HORSES.

SPECIFICATION forming part of Letters Patent No. 423,566, dated March 18, 1890.

Application filed September 18, 1889. Serial No. 324,292. (No model.)

To all whom it may concern:

Be it known that I, ALFRED MENDEL, a subject of the King of Saxony, and a resident of Strehlen, near Dresden, Saxony, Germany, 5 have invented certain new and useful Improvements in Collars for Horses, of which the following is a specification.

In horse-collars as heretofore made the collar rests wholly or partly on the fleshy part 10 of the neck, and in case where it does not fit properly it causes abrasion of the skin and very often rubs off part of the mane, while the part bearing on the neck in nowise assists the draft.

15 In order to make the ordinary horse-collar fit as exactly as possible to the form of the shoulders and neck, it is sometimes made to rest on a pad. The collar has thus hitherto been mainly carried by the neck of the horse, 20 and it is this that I wish to avoid.

According to my invention I shift the weight 25 of the collar onto the part of the horse which is best adapted for carrying the same—viz., the back; and to this end my invention consists in a modified form of breast-collar, the front portion of which rests against the shoulder-blade and is continued around the sides of the horse's back to a saddle which rests on 30 the back of the animal. The "collar" and saddle are movably connected by a pivot-joint, and I prefer to make the front of the 35 collar movable also by means of a hinge-joint, so that when the horse is pulling and drawing a load the collar shall not present an absolutely-rigid mass, but conform to the contour of the body and possess the desired play for the alternate lateral leg movements.

In the drawings, Figure 1 is an elevation, 40 and Fig. 2 a plan view, illustrating my invention.

The plates or parts *a a* of my collar are similar and are united in front of the chest by a hinge or link *b*. Each plate *a* is of metal, wood, or other suitable material, and may extend in one piece to the saddle *c*, or said plates 45 may wholly or partly consist of open-work frames *d*.

In the drawings this collar is shown by way of example as made of metal plate *a*, con-

nected to the saddle *c* by open-work frames 50 *d*. The plate *a* or the open-work frames are movably fastened to the saddle *c*. This may be done by a screw-bolt *e*, having a head as flat as possible and passed from within through one of the holes provided in the saddle. 55 The bolt goes through a slot in the plate or frame and has a nut, which, however, is not screwed down so tight as to prevent the plate or frame having a little play.

A number of holes are provided in the saddle, in order that the connection of the plate *a* or frame *d* with the saddle may be adjusted as desired to fit the form of the horse. The saddle *c* may consist of a plate portion having, by preference, a felt or leather flap or 60 lining underneath. The saddle with the flap or lining may be held in place by a belly-band. Where the plate *a* or frame *d* rests against the horse it is padded as required.

The shape of the plate *a* or frame *d* on each 70 side of the horse may, if desired, be varied, so as to follow or deviate from a direct line to the saddle *c*. They might assume a more upward direction from the chest and then a horizontal direction, or nearly so, to the saddle *c*. In such form a larger part of the collar may be made to rest against the shoulder-blade, through which the power is exerted on 75 the collar; also, in such form the parts *a* and *d* on each side of the horse may be connected 80 by a metal or wooden bow or strap over the neck of the horse, for the purpose of preventing the side parts of the collar from bending or expanding, but without the bow or strap resting on the horse's neck. The traces may 85 be hooked to any suitable part of the plates or frames *d*.

My improved collar is especially adapted 90 to horses, but can be made applicable to all draft-animals—such, for example, as mules.

I claim as my invention—

1. The combination, with the saddle, of the padded collar-plates *a*, connected together at the front ends, the frames *d*, fastened to the plates and extending to the saddle, and an 95 adjustable connection between the rear ends of such frames and the saddle, substantially as specified.

2. A collar for horses, consisting of the padded plates *a*, the link *b*, connecting the plates at the front, the frames *d*, connected at one end to the plates *a*, the saddle *c*, having adjustment-holes and a girth, and a connection between the back ends of the frames *d* to the saddle, substantially as set forth.

In testimony that I claim the foregoing as my invention I have signed my name in presence of two subscribing witnesses.

ALFRED MENDEL.
